METAL GALLERY

Philip E. Kettell, North Kingstown, R.I., assignor to E. A. Adams & Sons Inc., Pawtucket, R.I., a corporation of Rhode Island

Filed June 25, 1965, Ser. No. 85,909

Term of patent 14 years

(Cl. D54—2)

The figure is an enlarged face view of a fragmentary portion of a metal gallery showing the repeating design with a border. The design may repeat as indicated to complete the gallery. The gallery is of conventional thickness and the other side not shown is intaglio with the front.

I claim:

The ornamental design for a metal gallery, as shown and described.
